UNITED STATES PATENT OFFICE.

LUKE WOODWARD, OF NOTTINGHAM, ENGLAND.

STOCKING OR HALF-HOSE AND METHOD OF MANUFACTURING THE SAME.

SPECIFICATION forming part of Letters Patent No. 244,352, dated July 12, 1881.

Application filed January 7, 1881. (No model.) Patented in England June 10, 1880.

To all whom it may concern:

Be it known that I, LUKE WOODWARD, a subject of the Queen of Great Britain, residing at Lee Works, Arkwright Street, Nottingham, England, have invented certain new and useful Improvements in Stockings or Half-Hose and Methods of Manufacturing the same, (for which I have received Letters Patent in England, No. 2,350, dated 10th June, 1880,) of which the following is a specification.

The object of this invention is to enable the feet of stockings and half-hose or socks to be manufactured at less cost than heretofore. The usual way of manufacturing stockings and half-hose on flat or straight knitting machines is, first, to make the leg-piece with two pieces to form the heel projecting from its end, and sometimes between these two heel-pieces a central piece to form the instep, as is represented by Figure 1 of the annexed drawings. Afterward the partially-formed stocking or half-hose is transferred to another machine for the lower part of the foot to be worked upon it. The ends of the two heel-pieces a a' are brought together and the inner sides of the heel-pieces a b a' b' laid onto a row of needles, and the bottom of the foot is then worked upon these needles. Afterward the end of the leg-piece, or of the central or instep piece, c c' , previously mentioned, is placed onto a row of needles, and a continuation of this piece is worked to form the upper part of the foot. The side edges of the upper and lower parts of the foot have subsequently to be seamed together by hand, or on a piecing or seaming machine, and the foot is then completed. Thus, when forming the foot in this manner, it is necessary to have two transfers of loops from one set of needles to others, and there are two seams to be pieced or sewed together.

In some cases, (in France more especially,) in place of forming the foot in the above manner, the leg-piece and the heel-pieces have first been formed. The central loops at the end of the leg-piece and the side edges of the heel-pieces (along the whole line from a to b b' and a' in Fig. 2) have then been placed onto one straight row of needles, and the whole, both top and bottom of the foot, has been worked upon them in one piece, and in order to make the foot to the shape required peculiar double narrowings

have been made at the sides near the toe end. Fig. 3 represents a portion of a foot-piece with this old double narrowing as it is made at the toe end. These peculiar double narrowings are expensive to make. They require double manipulation, and cannot be made by automatic narrowing machinery, except by a very slow and expensive process, requiring complicated mechanism. In producing a double narrowing, instead of only one set of loops being lifted from the needles, as in making the single narrowing, hereinafter described, the loops near the selvage are removed from the needles in two separate sets, and then the outer set is moved to bring it to overlap the inner set, which is also moved before the retransfer of the loops from the narrowing-points to the needles is effected, to bring it to overlap the work which throughout has remained upon the needles.

The object of my invention is to enable properly-shaped foot-pieces of stockings and half-hose to be made in one piece upon ordinary knitting-machines provided with ordinary automatic narrowing apparatus. (See, for instance, the English patents of Hind *et al.*, No. 325 of 1854, and Woodward, No. 3,674 of 1869, for suitable narrowing apparatus; and for examples of machines of the class with which said apparatus may be employed, see the English patents of Lamb and Lowe and of Woodward, Nos. 3,068 and 3,480, both in the year 1871.)

I form the stocking or half-hose in the manner indicated by Fig. 4. I make single narrowings at the instep and near the toe of the foot-piece, at a distance in from the selvage nearly but not quite equal to the length of the side of the heel-pieces, or about one-fourth of the needles employed to make the foot. The work, when in the state indicated in Fig. 2, is transferred to the needles of the machine by which the foot is to be produced. The foot is commenced as in the French process above referred to, and continued as far as the point d' , where the first narrowing occurs. One broad set of points, containing about one-fourth of the number of needles employed to make the foot, then takes the loops of this band of fabric from the needles at one edge of the piece, and, after shifting them inward the distance of two needles, lands them onto other

needles. Similarly, on the other side of the fabric, another set of points shifts the loops on the other edge of the piece. The next narrowing occurs at d^2 , and here the operation is identically that performed at d' , except that the number of loops shifted is less by one. In the example given by the drawings three other narrowings, d^3 , d^4 , and d^5 complete the shaping of the instep, and at each successive narrowing the number of loops shifted is one less than in the preceding. These narrowings may be placed nearer to the selvage of the work, if desired. Similarly, when making the narrowings for shaping the toe, the number of loops shifted at the successive narrowings is gradually decreased as the toe end is approached. In this way the narrowings are kept all in one line directed to the toe, and this line is about one-quarter of the circumference of the foot from the selvage. The narrowings at the toe end occur at the points marked $e\ e\ e$, &c., in the figure. These narrowings are much more numerous and closely set than they are in the instep; but in other respects the shaping at the toe is effected in the same way as that at the instep. By thus using a broad set of points at each edge of the fabric, simply to take a large number of loops and shift them all inward toward the central line of the foot-piece, the narrowings will be made at the requisite distance from the selvage. These sets of points can be worked by the ordinary narrowing mechanism, just in the same manner that narrowings are commonly made automatically in all flat or straight knitting machines.

By making the feet of stockings in the above manner they can be made upon any ordinary flat or straight knitting machines fitted with narrowing mechanism, and there will be only one transfer of the work from one machine to another, and one seam to be pieced or sewed to connect together the selvages of the foot-piece. This seam runs along the center of the foot on the under side, as represented at Fig. 5, which is an under-side view of the foot of the completed stocking or half-hose. It will be observed that in this view the points $d'\ d^2$, &c., $e\ e$, &c., fall on the edge of the figure. Lines are drawn upon Figs. 4 and 5 to indicate the direction in which the "wales" or lines of loops in the fabric run. The lines marked on the one figure correspond to the lines on the other figure. In consequence of but one transfer of the work being required, and but one seam, my improved stockings and half-hose or socks having the foot-pieces as described above, which are conveniently produced by automatic machinery, can be made at less cost than any other of equal quality.

Along each of the sides of the foot-piece, and for some distance inward toward the center of the piece, the work may be thickened by the laying in of a splicing or thickening thread, leaving the central part of the piece, which

forms the top part of the foot or instep, the same thickness as the leg part, until the part is reached where the narrowings commence for shaping the toe. The top part of this portion of the foot can then also be spliced or thickened, so making a thin instep and thickened toe and foot bottoms.

Having thus described the nature of my said invention and the manner of performing the same, I would have it understood that I claim—

1. As an improvement in the art of manufacturing stockings, &c., the before-described method of working the foot all in one piece, or so that there is required but a single seam, and that in the middle of the foot on the underside, 80 said method consisting in placing the work, when ready to be transferred, or in the state indicated by Fig. 2, all at once upon the needles of the machine by which the foot is to be produced, with the loops of the two parts of 85 the heel and the middle or instep portion in a straight line upon them, shaping the instep by making single narrowings, as indicated at d' d^2 , &c., of Figs. 4 and 5, by taking loops from the needles at the edges of the piece, shifting 90 them inward the distance of two needles and landing them onto other needles to form the first of the single narrowings at opposite sides, forming the next of the narrowings, d^2 , in like manner, except that the number of loops shifted 95 is less by one than at first, and so on to complete the instep by successively producing single narrowings and lessening by one the number of loops in turn shifted, and finally shaping the toe by numerous closely-set narrowings, similar to those formed at the instep, and in line therewith, substantially as hereinbefore set forth.

2. The hereinbefore-described stocking, &c., having the single narrowings at the sides of 105 the instep and toe, those at either side of the instep being in line with those at the toe on the corresponding side, and provided with but a single seam which passes along the foot on the under side, substantially as hereinbefore set forth.

3. A stocking or sock provided with a number of single narrowings, e , at or near the toe, the said narrowings being in two series, and those of either series as they successively approach the toe correspondingly approaching the selvage to locate all of the narrowings about one-quarter of the circumference of the foot from the selvage, substantially as hereinbefore set forth, whereby the single seam of 115 the foot-piece may be formed at the under side.
